UNITED STATES PATENT OFFICE.

JAMES A. BURDEN, OF TROY, NEW YORK.

MECHANISM FOR CONVERTING CONTINUOUS ROTARY MOTION INTO INTERMITTENT ROTARY MOTION.

SPECIFICATION forming part of Letters Patent No. 608,573, dated August 9, 1898.

Application filed December 16, 1897. Serial No. 662,141. (No model.)

To all whom it may concern:

Be it known that I, JAMES A. BURDEN, of the city of Troy, county of Rensselaer, and State of New York, have invented a new and useful Mechanism for Converting Continuous 5 Rotary Motion into Intermittent Rotary Motion, of which the following is a specification.

My invention relates to a mechanism whereby rotary shaft motion which is continuous when actuated may be utilized to produce intermittent rotary motion and in such a manner that when applied to heavy machinery it can be used without jarring or concussion at the intervening periods of motion and rest. My improved means for accomplishing these results are more particularly adapted to be used in connection with the continuously-moving driving-shaft of machines producing horseshoes from a bar of iron by a series of connected operations, although it may be used in other kinds of machinery where like movements are called for.

In carrying out the purposes of my invention a gear-wheel mounted upon a proper shaft and arranged to mesh into a spur-wheel is used, and this gear-wheel is arranged to intermittently move the spur-wheel at regular intervals by the following means: There are constructed upon each of the opposite 25 sides of this gear-wheel arms radially extended therefrom so as to project beyond the perimeter of the gear-wheel, and upon a driving-shaft which moves continuously when actuated there are arranged two cams which 30 are keyed to said shaft, each of these cams being the counterpart of the other in cam-engaging surface, but each of which is mounted upon said shaft with its cam-engaging surfaces oppositely placed, one of these 35 cams acting as a motor-cam and in such a manner as to engage with one of the arms where extending beyond the edge of the gear-wheel, upon one side of the latter, and to so move the gear-wheel, while the other cam 40 upon the opposite side of it will engage with one of the arms thereat and thus regulate the movement of the gear-wheel as actuated by the motor-cam to prevent its acquiring momentum and to steady its action, and so soon 45 as the arms have passed from off the motor and steadyng cam a pivoted lever actuated

by a cam-groove formed in the face of a wheel on the continuously-moving shaft causes a spring stop-pin to rise and to elastically engage with one of the arms to stop the gear-wheel, while at the same instant a pawl on the frame supporting the shaft of the gear-wheel shaft engages with a ratchet-wheel on the hub of the gear-wheel to prevent the spring on the stop-pin from reversing the 60 gear-wheel.

Accompanying this specification to form a part of it there are three sheets of drawings containing six figures illustrating my invention with the same designation of parts by 65 letter reference used in all of them.

Of the illustrations, Figure 1 is a side elevation of the apparatus, with the frame supporting the spur-gear shaft shown as broken out to illustrate the parts back of it. Fig. 2 70 is a side elevation of the same mechanism shown at Fig. 1, but with the side opposite to that shown at Fig. 1 facing the view and with parts of the gear-wheel and spur-wheel where meshing into each other shown in section, and illustrating a beveled-gear connection made with the spur-wheel. (Not shown at Fig. 1.) Fig. 3 is an end elevation of the part of the apparatus showing the gear-wheel, taken in section between its radial arms, with 80 the continuously-moving shaft part shown in side elevation, with the arm-motor cam and the arm-steadying cam and the cam operating the pivoted lever to raise the stop-pin shown in end elevation. Figs. 4 and 5 are 85 vertical sections of the spring stop-pin and frame in which it is operated to rise and fall by the action of the pivoted lever actuating it, it being shown at Fig. 4 as raised and in a position to engage with one of the radial arms 90 of the gear-wheel and at Fig. 5 as having engaged with one of said arms. Fig. 6 is a perspective of the stop-pin and its slide-plate removed from the slide in which it is operated by the pivoted lever.

The several parts of the apparatus thus illustrated are designated by letter reference, and the function of the parts is described as follows:

The letter C designates the continuously-moving driving-shaft, and A the arm-actuating or motor cam secured to so as to turn

with the shaft C. The letter B designates the braking or retarding cam, also secured to and so as to turn with the shaft C.

The letter D designates the gear-wheel, and 5 f its spur-wheel.

J' designates beveled or miter gears transferring motion from the spur-wheel f to the shaft R', journaling in the frame S.

The letter K designates the shaft of the 10 gear-wheel D, and G the radial arms arranged on one side of the latter, and II the radial arms arranged upon the other side.

The letter M designates a wheel secured to the shaft C, having a cam-groove g² formed 15 in its side.

The letter L designates a lever, one end of which is provided with a cam-roller d², adapted to run in the cam-groove g², formed in the inside face of the wheel M, and the letter q 20 designates a pedestal in which this lever L is centrally pivoted. This lever L at its end opposite to that where actuated by the cam-groove g² has mounted thereon a pin p², arranged to move up and down in the recess d, 25 formed in the slide-plate P, so as to move the latter and the pin N upwardly and downwardly in a slideway formed in the inclined stand O, as actuated by the engagement of said lever with the cam-groove g².

30 The letters T designate a ratchet-wheel arranged on the hub of the spur-wheel D, and W a pawl pivoted to the standards b, in which the shaft K journals.

The letter U designates a leaf-spring arranged 35 on the side of the stop-pin N.

The operation of the mechanism thus described is as follows: The shaft C being actuated to turn in the direction of the arrow shown thereon at Fig. 1 with continuous motion, the cam A, secured thereto, will engage 40 with the curved end h' of that one of the arms G which is next adjacent, and by such engagement will actuate the gear-wheel D to turn and also rotate the spur-wheel f while

45 this engagement of the cam A and the arm G continues. When the cam A commences to engage with the adjacent arm G, the gear-wheel moves slowly, but increases in speed from the shape of the cam-surface as the engagement continues, and this would tend to give to the gear-wheel a momentum and impetus not desirable; but to remedy this condition while the motor-cam is operating the arm G on its more acute surfaces one of the 50 arms II commences to run on the reversely-arranged surface of the cam B, which prevents the gear-wheel from taking on momentum. When the engagement of the cams A and B with the arms has ceased, the pivoted lever L,

55 as actuated by the cam-groove g², actuates the plate P and causes the spring stop-pin N to rise in the slideway formed in the incline O, with the spring u elastically engaging with one of the arms G to stop the gear-wheel, and 60 the instant the stop is thus made the ratchet-wheel T and pawl W engage to hold the gear-wheel at rest.

As illustrated at Fig. 1, while the motor-cam A is engaging with the arm G at the commencement of the cam curve a' to move the gear-wheel D the outer end of the next adjacent and following arm II commences to run on that surface of the cam B at a² which is just the reverse of that on the cam A operating the arm G; but this engagement of the arm II and cam B, (indicated at a²), it will be seen, is only one of sliding contact without propulsion, and it thus acts to steady the movement of the wheel D, so as to prevent it from acquiring momentum, as the accelerating pitch of the cam A acts with increasing speed on the arm G, with the arm II and cam B acting as a brake. The arms G upon one side of the gear-wheel D, as shown in this instance of their use, are arranged at regular 85 distances apart, thus dividing the perimeter of the wheel into six equal parts, with the cam-engaging curved end edges h' of these arms G diametrically in line with each other and the center of the gear-wheel D, and the arms II, of which in this instance of their use there are six, arranged upon the gear-wheel D, on the side opposite to those indicated at G, and these arms II are arranged on the gear-wheel D, with their cam-engaging end edges e diametrically in line with the center of the gear-wheel D; but each of these arms II is arranged enough nearer to that one of the arms G with which it coöperates than the next adjacent arm II to have each coöperating pair 90 of arms G and II operated upon simultaneously by the oppositely-facing cams A and B, actuated by the same shaft C. As thus constructed each simultaneous engagement of the cams A and B with each adjacent pair of arms G and II, as before described, moves the gear-wheel D one-sixth of a revolution and actuates the spur-wheel f and its connection half a turn.

While I have shown and described the radially-arranged arms G upon the gear-wheel D as actuated by the cam A upon the continuously-moving shaft C, in connection with the arms II and cam B, if desired the two latter factors may be omitted in light-running 115 machinery and the lever L, the spring stoppin N, with the ratchet-wheel T and pawl W, used in connection with the arms G and cam A with the cam B and arm II.

As thus constructed and arranged to be 120 operated heavy or light running machinery may be operated with regular intermittent periods of motion and rest and when applied to ponderous machinery all jamming or concussion consequent upon starting and stopping is avoided.

Having thus described my invention, what I claim, and desire to secure by Letters Patent, is—

1. A gear-wheel having bearings in which 130 to journal and provided with a spur-wheel into which it meshes; radially-arranged arms constructed upon one of the gear-wheel sides; a driving-shaft adapted to be rotated con-

tinuously; a cam on said driving-shaft, constructed to engage in sequence with each of said arms to move it, and the gear-wheel part of a turn, at each revolution of said driving-shaft; and a spring stop-pin operated by said driving-shaft to engage with one of said arms to arrest and limit the measure of movement made by said gear-wheel, and then to disengage therefrom, substantially as shown and described.

2. The combination with a gear-wheel provided with bearings in which to journal, and having a spur-wheel into which it meshes; of radially-arranged arms constructed upon one side of said gear-wheel; a driving-shaft adapted to be rotated continuously; a cam on said driving-shaft, constructed to engage in sequence with each one of said arms to move it, and the gear-wheel part of a turn at each revolution of said driving-shaft; a spring stop-pin operated by said driving-shaft to arrest and limit the measure of each of the movements made by the arm and gear-wheel; and a ratchet-wheel arranged on the gear-wheel hub, and provided with a pawl whereby the detention of the gear-wheel at each period of rest may be positive, substantially as and for the purposes set forth.

3. In a mechanism for converting continuous rotary motion into intermittent rotary motion, the combination with a gear-wheel having bearings in which to journal, and a spur-wheel into which it meshes; of radially-arranged arms on each side of said gear-wheel; a driving-shaft adapted to turn with continuous rotation, and provided with two cams, one of the latter adapted to engage with one of said arms to move it, and said gear-wheel a part of a turn at each revolution of said shaft; and the other cam to make a sliding contact with one of the radial arms upon the other side of the gear-wheel to act as a brake; a spring stop-pin operated by said shaft to arrest and limit each movement of the gear-wheel; and a ratchet-wheel arranged on the hub of the latter, and provided with a pawl adapted to detain the wheel as arrested in movement by the spring stop-pin, substantially as shown and described.

4. The combination with a gear-wheel having bearings in which to journal, and a spur-wheel into which it meshes; of radially-arranged arms constructed upon each side of said gear-wheel, substantially as described; a driving-shaft adapted to be rotated continuously; two cams each provided with the same curvature of cam-surface; but mounted oppositely on said driving-shaft, with one of said cams so positioned by its cam-surface as to engage with one of said arms to move it, and the gear-wheel, part of a rotation at each revolution of said driving-shaft; and the other cam by means of the reverse position of its curved surface making a sliding engagement with one of the arms upon the other side of the gear-wheel, and thus acting as a brake to prevent the gear-wheel from

acquiring momentum, substantially as shown and described.

5. The combination with the gear-wheel D, having the spur-wheel f, into which it meshes, and constructed with the radially-arranged arms G, upon one of its sides; of the driving-shaft C, adapted to be rotated continuously; the cam A, mounted upon said driving-shaft 75 and constructed substantially as described; the incline O, the stop-pin N, mounted in the latter; the lever L, and the cam-groove wheel M, mounted upon the driving-shaft, constructed and arranged to be operated substantially in the manner as and for the purposes set forth.

6. The combination with the gear-wheel D, having the spur-wheel f, into which it meshes, and constructed with the radially-arranged arms G, upon one of its sides, of the driving-shaft C, adapted to be rotated continuously; the cam A, mounted upon said driving-shaft 85 and constructed substantially as described; the incline O; the stop-pin N, mounted in the latter; the lever L, the cam-groove wheel M, mounted on said shaft, and the ratchet T, and pawl W, constructed and arranged to be operated substantially in the manner as and for the purposes set forth.

7. The combination with the shaft C, arranged to be actuated with continuous rotation; of the cams A and B, mounted thereon relatively constructed and positioned, substantially as described; the gear-wheel D, having the spur-wheel f, into which it meshes, and provided with the radially-arranged arms G, mounted upon one of its sides, and the radially-arranged arms H, upon the other side; the incline O, and the stop-pin N, mounted 100 in the latter, constructed and arranged to be operated substantially in the manner as and for the purposes set forth.

8. The combination with the shaft C, arranged to be actuated with continuous rotation; of the cams A and B, mounted thereon and relatively positioned and constructed, substantially as described; the gear-wheel D, having the spur-wheel f, into which it meshes, and provided with the radially-arranged arms 110 G, mounted upon one of its sides, and the radially-arranged arms H, upon the other side, and the ratchet-wheel T, arranged on the gear-wheel hub, and provided with a pawl, the incline O, and the stop-pin N, arranged in the latter, constructed and arranged to operate, substantially in the manner as and for the purposes set forth.

9. The combination with the continuously-moving shaft C, having mounted thereon the cams A and B, each constructed and positioned thereon relatively to each other substantially as described; of the gear-wheel D, meshing into the spur-wheel f, and having mounted upon one of its sides the radially-arranged arms G, and upon the other side, the radially-arranged arms H; the incline O, the stop-pin N, mounted to slide in the latter; the lever L, and the cam-groove wheel M,

mounted on the driving-shaft, constructed and arranged to operate substantially in the manner as and for the purposes set forth.

10. The combination with the continuously-moving shaft C, having mounted thereon the cams A, and B, each constructed and positioned thereon relatively to each other, substantially as described; of the gear-wheel D, meshing into the spur-wheel f, and having 5 mounted upon one of its sides the radially-arranged arms G, and upon the other side the radially-arranged arms H; the incline O, the stop-pin N, mounted to slide in the latter; the 10

lever L, and the cam-groove wheel M, mounted on the driving-shaft, and the ratchet-wheel T, mounted upon the gear-wheel hub, and provided with the pawl W, constructed and arranged to operate, substantially in the manner, as and for the purposes set forth.

Signed at Troy, New York, this 7th day of December, 1897, in the presence of the two witnesses whose names are hereto written.
